UNITED STATES PATENT OFFICE

108,897

DESIGN FOR A COMBINED SINK AND CABINET

Jacques Stanitz, Warren, Ohio, assignor to Mullins Manufacturing Corporation, Salem, Ohio, a corporation of New York

Application June 26, 1937, Serial No. 70,080

Term of patent 7 years

To all whom it may concern:

Be it known that I, Jacques Stanitz, a citizen of the United States, residing at Warren, in the county of Trumbull and State of Ohio, have invented a new, original, and ornamental Design for a Combined Sink and Cabinet, of which the following is a specification, reference being had to the accompanying drawings forming part thereof.

Figure 1 is a front perspective view of a combined sink and cabinet, showing my new design, the faucet discharge arm being swung to one side;

Fig. 2 is a top plan view thereof, with the faucet discharge arm swung centrally between the faucet valve handles;

Fig. 3 is an angled perspective view thereof; and Fig. 4 is an end elevation thereof.

I claim:

The ornamental design for a combined sink and cabinet, as shown and described.

JACQUES STANITZ.
